UNITED STATES PATENT OFFICE.

EDWARD W. BURGESS, OF CHICAGO, ILLINOIS, ASSIGNOR, BY MESNE ASSIGNMENTS, TO INTERNATIONAL HARVESTER COMPANY, A CORPORATION OF NEW JERSEY.

CUTTING APPARATUS FOR MOWING-MACHINES.

1,308,162.

Specification of Letters Patent.

Patented July 1, 1919.

Application filed July 5, 1916. Serial No. 107,677.

To all whom it may concern:

Be it known that I, EDWARD W. BURGESS, a citizen of the United States, residing at Chicago, in the county of Cook and State 5 of Illinois, have invented certain new and useful Improvements in Cutting Apparatus for Mowing-Machines, of which the following is a full, clear, and exact specification.

My invention relates to cutting apparatus 10 for mowers, and in particular to an improved construction of the knife head; its object being to provide a knife head formed from soft steel that will be both light and strong and cheaply made.

15 This object is attained by means of the construction illustrated in the accompanying drawing, in which—

Figure 1 is a front elevation of a sheet steel blank having an angular cross section 20 and spaced semi-spherical bosses upon its vertical web;

Fig. 2 is a top plan view of the blank after it has been given a curved form;

Fig. 3 is a top view of the complete head; 25 and

Fig. 4 is a cross section of Fig. 2 in the direction of the arrows.

The same reference characters designate like parts throughout the several views. 30 The blank is first formed with horizontally and vertically disposed webs 5 and 6, respectively, the horizontal web having a widened angular portion 7 extending from one end of a shank 8 and forming a head portion that is separated from a narrower flanged portion 9 by a gap 10, and 11 represents alined openings in the shank 8 whereby by the head may be secured to a knife back (not shown). The blank is then given the 35 form shown in Fig. 2, with semi-spherical bosses 12 struck from the head portion of the vertical web upon opposite sides of the gap 10. The vertical web is then turned at the gap 10 in a direction to fold it together, 40 bringing the narrower flanged portion 9 in rear of the angular portion 7 and the semi-spherical bosses 12 in alined position to form a ball bearing for a pitman connection, as shown in Fig. 3.

50 The improved structure is light and

strong, cheaply made, durable and efficient in operation.

Having shown and described a preferred embodiment of my invention, I do not desire that it be confined to the specific details 55 of the structure as illustrated, it being understood that changes may be made in the form, proportion and organization of its parts without departing from the spirit of my invention as indicated by the scope of 60 the appended claims.

What I claim as my invention, and desire to secure by Letters Patent, is:

1. A knife head having horizontally and vertically disposed web members, the vertical portion comprising two sections and being provided with alined separately formed outwardly projecting bosses having semi-spherical bearing surfaces on their outer 65 faces. 70

2. A knife head having horizontally and vertically disposed web members, said vertical web comprising two parallel members having alined outwardly projecting bosses having semi-spherical bearing surfaces on 75 their outer faces.

3. A knife head having horizontally and vertically disposed web members, said vertical web comprising two parallel integrally connected contacting members, said members having alined outwardly projecting semi-spherical bosses. 80

4. A blank from which a knife head may be formed, having a vertical web and a plurality of separated horizontal webs extending on the same side of said vertical web, and semi-spherical bosses projecting outwardly from said vertical web, one of said bosses being disposed over each of said horizontal webs. 85 90

5. A blank from which a knife head may be formed including horizontally and vertically disposed web members, said horizontal web having a widened end portion and provided with an open gap intermediate its ends and extending toward said vertical web, and semi-spherical bosses projecting outwardly from the face of said vertical web upon opposite sides of said gap. 95

6. A knife head having horizontally and 100

vertically disposed web members, said vertical web being doubled upon itself at one end and provided with aligned semi-spherical bosses forming a ball bearing for a pitman connection.

7. A knife head having horizontally and vertically disposed web members, said ver-

tical web being turned back upon itself at one end thereof and provided with oppositely disposed semi-spherical bosses upon 10 said end forming a ball bearing for a pitman connection.

In testimony whereof I affix my signature.
EDWARD W. BURGESS.
